(57) **CLAIM**

The ornamental design for an air freshener device, as shown and described.

DESCRIPTION

FIG. 1 is a perspective view of the air freshener device with environmental structure in the form of a bottom attachment; FIG. 2 is a front view thereof; FIG. 3 is a left-side view thereof; FIG. 4 is a rear view thereof; and FIG. 5 is a right-side view thereof; FIG. 6 is a top view thereof; FIG. 7 is a bottom view thereof; FIG. 8 is a perspective view of the air freshener device with environmental structure in the form of a top cover and a bottom attachment; FIG. 9 is a front view thereof; FIG. 10 is a left-side view thereof; FIG. 11 is a rear view thereof; FIG. 12 a right-side view thereof; FIG. 13 is top view thereof; FIG. 14 is a bottom view thereof; FIG. 15 is a perspective view of the air freshener device with environmental structure in the form of another bottom attachment; FIG. 16 is a front view thereof; FIG. 17 is a left-side view thereof; FIG. 18 is a rear view thereof; and FIG. 19 is a right-side view thereof; FIG. 20 is a top view thereof; FIG. 21 is a bottom view thereof; FIG. 22 is a perspective view of the air freshener device with environmental structure in the form of a top cover and another bottom attachment; FIG. 23 is a front view thereof; FIG. 24 is a left-side view thereof; FIG. 25 is a rear view thereof; FIG. 26 a right-side view thereof; FIG. 27 is top view thereof; and, FIG. 28 is a bottom view thereof.

The broken lines illustrate environmental structure and form no part of the claimed design. The dot-dash broken lines define the bounds of the claimed design and form no part thereof.

The drawings include surface shading that illustrates contour and not surface ornamentation.
